UNITED STATES PATENT OFFICE.

ARTHUR WEST, OF CANANDAIGUA, NEW YORK.

NON-SLIP GRIP FOR BATHTUBS.

1,329,487.

Specification of Letters Patent.

Patented Feb. 3, 1920.

Application filed April 7, 1919. Serial No. 287,995.

To all whom it may concern:

Be it known that I, ARTHUR WEST, a citizen of the United States, residing at Canandaigua, in the county of Ontario and State of New York, have invented certain new and useful Improvements in Non-Slip Grips for Bathtubs, of which the following is a specification.

This invention relates to hand grips for bath tubs and similar containers and has for its object the provision of a comparatively simple and inexpensive device of this character, capable of being readily attached to or detached from the rim of a bath tub and which, when in position thereon, will present a roughened surface at the rim of the tub which may be conveniently grasped by the bather to prevent slipping or falling during the bathing operation or when leaving the tub after a bath.

The invention further aims to provide a hand grip including a tubular body having an attaching flange adapted to fit beneath the rim of a bath tub and provided with a depending portion which extends within the tub and frictionally engages the inner wall thereof for holding the hand grip in position on said rim.

The invention further contemplates providing the inner surface of the hand grip with a covering of yieldable material to prevent scratching or otherwise marring the polished surface of the tub.

A still further object is generally to improve this class of devices so as to increase their utility, durability and efficiency.

Figure 1 is a perspective view of a portion of a bath tub showing my improved hand grip applied thereto;

Fig. 2 is an enlarged transverse sectional view;

Fig. 3 is a perspective view of the hand grip detached and looking at the lower side thereof.

Corresponding and like parts are referred to in the following description and indicated in all the views of the drawings by the same reference characters.

The improved hand grip forming the subject matter of the present invention may be applied to bath tubs and similar containers and by way of illustration is shown in con-

nexion with a bath tub of the ordinary construction in which 5 designates the body of the tub and 6 the rim.

55

The device comprises a tubular member 7 preferably stamped or otherwise formed into substantially cylindrical shape from a single length of resilient material and having its longitudinal edges spaced apart to 60 form an opening 8 at the bottom thereof and extending the entire length of the tubular member, as shown. One edge of the metal of which the tubular member is formed is bent inwardly to form an attaching flange 9 adapted to extend beneath and frictionally engage the rim 6 of the bath tub, while the other longitudinal edge of the tubular member is bent or deflected upwardly at an angle thereto to form a flange 65 10 adapted to bear against and frictionally engage the inner wall of the tub. The exterior of the tubular member 7 is preferably covered by a strip of longitudinally corrugated rubber or other yieldable material 11 70 so as to form a roughened surface which may be conveniently grasped by the bather to prevent slipping or falling during the bathing operation or when leaving the tub after a bath. The yieldable covering 11 is 75 retained in position on the exterior of the tubular member 7 by bending the metal at the outer edges of the flanges 9 and 10 to produce hooked portions 12 which receive the adjacent ends of the covering 11, as best 80 shown in Fig. 2 of the drawings. Arranged within the tubular member and secured thereto by glue or other adhesive is an inner lining 13 also preferably formed of corrugated rubber and which serves to prevent 85 scratching or otherwise marring the polished surface of the rim of the tub when the hand grip is applied thereto. The inner covering 13 preferably terminates short of the free end of the flange 10, as indicated at 90 14, so as not to interfere with the resiliency of the tubular member and thus permit the flange 10 to frictionally engage the inner wall of the tub with a sufficient degree of firmness to hold the hand grip against accidental displacement on said rim. The main body of the tubular member 7 is curved to conform to and encircles the major portion 95 of the rim of the tub, while the flanges 9

100

and 10 by engagement with the edge of the rim and inner wall of the tub retain the grip in position thereon.

In using the device, the flange 9 is inserted under the longitudinal edge of the rim 6, after which the main body portion thereof is expanded slightly and passed over the upper surface of the rim and in which position the flange 10 will frictionally engage the inner wall of the tub with sufficient firmness to hold the hand grip thereon, as previously stated. It will here be noted that the hooked terminal 12 of the attaching flange 9 produces a raised portion or shoulder 15 at the terminal of the flange which shoulder bears against the lower longitudinal edge of the rim of the tub and assists in holding the device in position on the tub. It will, furthermore, be noted that owing to the fact that the inclined flange 10 is spaced from the inner wall of the tubular member 7, the outer wall of said tubular member will present a yieldable surface or cushion within the tub and thus prevent injury to the bather. The material forming the outer and inner coverings 11 and 13 is preferably extended longitudinally beyond the adjacent ends of the tubular member so as to house and protect the metal and prevent the sharp edges thereof from coming in contact with the bather and cutting or otherwise lacerating the flesh.

While the device is preferably constructed from a single sheet of resilient metal it will, of course, be understood that the hand grips may be molded or otherwise formed from gutta-percha or other suitable material possessing the requisite resiliency to retain the hand grip in position on the rim of a tub. It will also be understood that the hand grips may be made in different sizes and shapes to conform to different styles of bath tubs and that the exterior of the tubular member may be provided with any desired roughened surface to prevent slipping of the hands when the grip is grasped in the act of raising or lowering one's self within the tub.

Having thus described the invention, what is claimed as new is:

50. 1. A hand grip including a longitudinally split tubular member adapted to fit over the rim of a bath tub and having its opposite longitudinal edges extended upwardly within said member to provide flanges, one of which is adapted for engagement beneath said rim and the other adapted to extend within the tub and frictionally engage the inner wall of said tub.
55. 2. A hand grip including a tubular member adapted to fit over the rim of a bath tub and provided with a roughened exterior surface, said member being provided with means for engagement beneath the rim and having one edge thereof extended upwardly

within the tubular member to form a flange adapted to bear against the inner wall of the tub, and a yieldable covering secured to the inner wall of the tubular member for contact with the adjacent wall of the tub. 70

3. A hand grip including a resilient tubular member curved to conform to and adapted to fit over the rim of a bath tub, one edge of said member being provided with an attaching flange for engagement beneath the 75 edge of the rim and another edge of said member being extended upwardly within said tubular member to form a flange adapted to frictionally engage the inner wall of the tub, and a covering for the inner and 80 outer walls of said tubular member.

4. A hand grip including a longitudinally split tubular member adapted to fit over the rim of a bath tub and having one edge thereof adapted to extend beneath the 85 lower edge of the rim and its opposite edge bent upon itself and extended upwardly within said tubular member and at an angle thereto to form a flange adapted to frictionally engage the inner wall of the 90 tub.

5. A hand grip including a longitudinally split tubular member having one edge thereof bent inwardly to form a flange adapted to fit beneath the edge of the rim of a bath 95 tub and its opposite longitudinal edge bent upwardly to form an inclined flange adapted to frictionally engage the inner wall of the tub, the material of which the tubular member is formed being bent upon itself 10 at said flanges to produce terminal hooks, and a covering extending over the exterior of the tubular member with its ends engaged by said hooks.

6. A hand grip including a longitudinally split tubular member having one edge thereof bent inwardly to form an attaching flange adapted to engage beneath the rim of a bath tub and its other edge bent inwardly and upwardly within the tubular member and at an angle to the attaching flange to form a flange adapted to frictionally engage the inner wall of the tub, a yieldable covering entirely surrounding the exterior of the tubular member, and a yieldable covering partially surrounding the interior of the tubular member.

7. A hand grip for bath tubs including a longitudinally split tubular member having one edge thereof bent inwardly to form an attaching flange adapted to extend beneath the rim of a bath tub and its other edge bent upwardly and inwardly in spaced relation to the inner wall of the tubular member and above the upper surface of the attaching flange to form a flange adapted to bear against the inner wall of the tub, and a yieldable covering for the inner and outer walls of the tubular member.

8. A hand grip including a longitudinally

split tubular member having its edges bent inwardly to form flanges, one of which is adapted to extend beneath the rim of a bath tub and the other to frictionally engage the inner wall of said bath tub, a yieldable covering for the inner and outer walls of the tubular member, means arranged at the terminals of the flanges for securing the

outer covering in position on the tubular member, the material at the securing means 10 of one of the flanges forming a shoulder adapted to bear against the inner edge of the rim of the tub.

In testimony whereof I affix my signature.

ARTHUR WEST. [L.S.]
